Application September 7, 1937, Serial No. 162,792

14 Claims. (Cl. 33—205)

Our invention relates to well bore measuring devices and has particular reference to a method and apparatus for determining the angle of inclination of a well bore from the true vertical.

In the art of drilling well bores, particularly oil well bores, it is important to ascertain from time to time whether the hole extends in the true vertical or has deviated from the vertical and to what extent the same has deviated from the vertical so that proper correction of the direction of the well bore may be made. Heretofore it has been the practice to interrupt the drilling operations from time to time for the purpose of measuring the direction in which the hole is being drilled and the apparatus heretofore employed for determining whether the hole has deviated from the vertical and to what extent have been complicated structures so delicate in their construction as to require extreme care in their manufacture, maintenance and handling during actual service.

Two general types of measuring or inclination detecting instruments have been employed, namely, those attached to the well drilling tools, in the case of reciprocating tool drilling, and, second, those types of devices which must be run into the well from the surface of the ground each time a measurement or detection is to be made.

The first type of these devices, namely, the type attached permanently to the drilling apparatus, has failed to function satisfactorily, primarily because of the delicacy with which the various parts of the instruments must be made in order to produce accurate indications, such delicate construction rendering the devices unsuitable for permanent location or attachment upon the drilling tools because the vibrations and shocks encountered by the instrument during the normal drilling operations is such as to rapidly destroy the instrument.

On the other hand, devices of the type insertable into the well bore from the surface of the ground require the shutting down of the drilling operations for an appreciable length of time, while the instrument is lowered and withdrawn. Then it must be opened and inspected in order to ascertain the angularity of the hole. Also such instruments have been so delicate that if allowed to fall into the bore and descend by unrestrained gravity, the instruments when brought to rest at the bottom of the bore receive such shocks as rapidly destroy the delicate portions of the instruments and render them either completely inoperative or of such short life that they must

be rebuilt or entirely replaced after a few indications have been made by the instruments.

It is therefore an object of our invention to provide an inclination detecting and measuring instrument of such rugged construction as will permit the instrument to withstand any of the normal vibrations or shocks encountered in the drilling of an oil well and of such character as to enable the instrument if desired to be dropped freely into the well bore without danger of wrecking the instrument when it strikes the bottom of the bore.

Another object of our invention is to provide an inclination detecting and measuring instrument which is relatively simple in construction and which may be contained within a housing adapted to dispose its longitudinal axis parallel with the axis of the well bore and in which the lateral cross sectional area of the instrument is relatively small as compared with the cross sectional area of the well bore.

Another object of our invention is to provide an instrument of the character set forth which may be attached to the boring bit or to any of the tools employed in the drilling operations and left so attached to the tools during the normal drilling operations and requiring merely a short pause in the drilling operations for the successful detection and measurement of any inclination of the well bore from the vertical.

Another object of our invention is to provide an instrument of the character set forth in the preceding paragraph wherein the instrument detects and measures the angle of inclination of the well bore without requiring the lifting or removing of the drilling tools out of the well bore.

Another object of our invention is to provide an instrument of the character set forth where in a plurality of angle measuring devices are employed, each of which measures a specific angle and the angle measured by each of the devices being different from that measured by the others so that the number of these devices which are actuated is representative of the angle between the longitudinal axis of the well bore and the true vertical.

Another object of our invention is to provide a device of the character set forth associated with an indicating or sounding mechanism which will transmit predetermined sound vibrations to the ground surface where these vibrations may be detected and interpreted to produce a translation of the angle of inclination of the well bore

in terms of signals or records at the ground surface.

Another object of our invention is to provide an instrument of the character set forth in the preceding paragraph wherein extraneous vibrations or sounds differing from the predetermined selected sounds may be filtered out so as not to interfere with the accurate reception and translation of the signals transmitted by the instrument.

Another object of our invention is to provide an instrument of the character set forth wherein a plurality of angle detecting devices may be inserted into the well bore, each of the angle detecting devices including a movable member such as a ball supported upon a dish-like surface, the supporting surface of each of the devices differing from those of the others in such manner as to allow the ball or movable member to roll from a predetermined position when the supporting surfaces are disposed at varying angles from a horizontal plane so that the number of balls or movable devices shifted from their normal positions represents the angle of inclination of the well bore to the true vertical.

Other objects of our invention and advantages thereof will be apparent from a study of the following specifications, read in connection with the accompanying drawings, wherein,

Fig. 1 is a diagrammatic elevational view of an oil well and drilling apparatus therefor, illustrating one manner of using our inclination detecting and measuring instrument;

Fig. 2 is a detail vertical elevational view, partly in section, of a boring tool and illustrating the manner in which our inclination detecting and measuring instrument may be associated therewith;

Fig. 3 is a horizontal sectional view taken along line III-III of Fig. 2;

Fig. 4 is a detail vertical perspective sectional view taken through our detecting and measuring instrument and illustrating the manner in which a plurality of angle detecting devices may be assembled within a slender elongated housing;

Fig. 5 is a detail horizontal sectional view through one of the angle detecting devices shown in Fig. 4, the section being taken along line V-V of Fig. 4;

Fig. 6 is a diagrammatic view illustrating the manner in which signal receiving, filtering, amplifying, translating and recording apparatus may be associated with the ordinary oil well drilling equipment and with our inclination detecting instrument to measure and translate the inclination in accordance with our method;

Fig. 7 is a diagrammatic view illustrating the electrical connections which may be employed with one form of our instrument to translate the measurements made by our instrument into terms of predetermined sound vibrations;

Fig. 8 is a detail vertical sectional view of a modified form of detecting device which may be substituted for the detecting devices illustrated in Figs. 4 and 5;

Fig. 9 is a detail sectional view similar to Fig. 8 and illustrating a still further modified form of detecting device which may be employed;

Fig. 10 is a vertical sectional view similar to Figs. 8 and 9 and illustrating a still further modified form of detecting device which may be employed;

Fig. 11 is a horizontal sectional view taken along line XI-XI of Fig. 10;

Fig. 12 is a vertical sectional view similar to Figs. 8, 9 and 10 and illustrating a still further modified form of detecting device which may be employed;

Fig. 13 is a diagrammatic view illustrating a modified system of electrical connections which may be employed to translate the angle measurements from the detecting devices into terms of sound vibrations;

Fig. 14 is a plan view of one of the angle detecting units which may be employed in place of the angle detecting units illustrated in Fig. 4 and illustrating the manner in which a number of these units may be so constructed that when assembled together they make electrical connections between the members to dispense with wires or other electrical conductors;

Fig. 15 is a vertical sectional view taken along line XV-XV of Fig. 14 and illustrating the manner in which electrical pin and socket connections may be employed to complete electrical circuits between several assembled detector units; and

Fig. 16 is a diagrammatic sectional view through a well bore and drilling apparatus and illustrating the manner in which our detecting instrument may be dropped or lowered into the well to make measurements without permanently attaching the instrument to the drilling apparatus.

Referring to the drawings, we have illustrated a typical well drilling installation in Fig. 1, in which a well bore 1 is illustrated as being in the process of being drilled by means of a drill bit 2 coupled in the usual manner to a sub 3 which is in turn connected at the lower end of a drill string 4 made up in the usual manner of a plurality of sections or lengths of drill pipe extending upwardly to the ground surface 5 where the drill string is coupled in any suitable manner to a rotary table 6 driven or rotated by means of power apparatus 7. The drill string 4 is supported upon a swivel 8 which is in turn suspended upon a traveling block 9 of a block and tackle assembly of which the stationary or crown block 10 is supported at the upper end of a derrick structure 11.

As is the usual practice in oil well drilling, the swivel 8 constitutes a means by which mud fluid or drilling fluid may be circulated down through the drill string 4 and upwardly about the drill string 4 to carry away the cuttings, the mud fluid being pumped into the drill string 4 by suitable well known pumping apparatus supplying this fluid through a mud hose 12 coupled to the swivel 8.

The well bore 1 in Fig. 1 is illustrated as being disposed in the true vertical throughout the major portion of its length but the lower end of the well bore 1 is illustrated as having been deviated from the vertical at the point 13 so that, should the drilling operations be continued under the conditions illustrated in Fig. 1, the well bore will not have its longitudinal axis extending along the true vertical but would instead extend at a considerable angle to the vertical.

As will be understood by those skilled in the art, whenever the well bore deviates from the true vertical, it may be brought back to a true vertical line by employing well known bore straightening methods, tools or instruments, provided that the operator or driller knows that the bore has deviated from the vertical and particu-

larly to what extent the bore has so deviated.

We provide an inclination detecting and measuring apparatus which will indicate to the operator the fact that the well bore has deviated from the vertical and to what extent and by employing this instrument the driller will know how to correct the improperly drilled hole and will be able to straighten the bore before serious deviation from the vertical can occur. It will also be understood by those skilled in the art that in most instances the direction of the deviation is not material since all that is necessary is that the driller know that there has been a deviation and he is warned to bring the hole back to a true vertical line.

We have illustrated herein an angle detecting and measuring instrument which comprises essentially a housing or container 14 which may be of any suitable size or shape though we prefer that the same comprise an elongated hollow cylinder open at both its ends and fitted with closures 15 and 16, preferably threaded into the ends of the housing 14, as indicated at 17 and 18, respectively.

The interior of the housing 14 constitutes an elongated chamber into which may be assembled a plurality of angle detecting devices or units 19a, 19b, 19c, 19d and 19e, it being understood that the number of detecting units 19a, 19b, etc. may vary as will be hereinafter more fully described.

Each of the angle detecting units constitutes switching apparatus adapted to close or to open an electric circuit dependent upon whether or not the longitudinal axis of the housing 14 is disposed in the true vertical or is disposed at an angle to the vertical.

In the form of the device illustrated in Figs. 4, 5 and 8 through 11, each of the units 19a, 19b, etc. comprises a disc-like member 20 having an upper surface 21 upon which a ball or other rolling member 22 is adapted to be supported, the surface 21 having a depression 23 therein into which the ball 22 normally seats when the housing member 14 is disposed with its longitudinal axis in the true vertical, but adapted to allow the ball to be displaced from its normal position when the housing 14 is tilted away from the true vertical.

In the form of the device illustrated in Figs. 4 and 5, the surface 21 is that of a conical depressed surface extending transversely to the longitudinal axis of the housing 14 so that the ball 22 will normally rest at the apex 23 of the cone, that is, centrally of the surface 21. The angle of inclination of the conical surface to the horizontal being such that if the housing 14 is tilted from the true vertical to an angle equal to the angle formed between the conical surface and the true horizontal, the ball 22 will roll from its normal or central position to an abnormal position away from the apex 23 of the conical surface.

Disposed above the member 20 is a contact ring 24 insulated from the member 20 by a pair of insulating rings 25 and 26, each of which may be constructed of a suitable annular member of insulating material having a recess 27 therein, the recesses of the rings 25-26 when assembled together defining a recess into which the contact ring 24 may seat and be held. When the ball 22 is moved from its normal or central position, the ball will be brought into contact with the contact ring 24 and, as will be hereinafter more

fully described, will electrically connect the ring 24 with the supporting member 20.

By referring particularly to Fig. 4, it will be noted that the uppermost unit 19a has its member 20 formed with a ball supporting surface substantially flat while walls of the conical surfaces 21 of each of the succeeding units 19b, 19c, 19d and 19e extend at a progressively increasing angle to the horizontal. Thus when the longitudinal axis of the housing 14 is disposed in the vertical, all of the balls 22 associated with the units 19a, 19b, etc. will be in their lowermost positions, namely, at the apices of their supporting members 20 while, if the housing 14 is tilted at a slight angle, the ball 22 associated with the unit 19a will be moved from its normal position to an abnormal position in contact with its associated contact ring 24. Further, if the housing 14 is tilted at a greater angle to the vertical, the ball associated with the unit 19b will move into contact with its contact ring, each of the balls being moved from its normal position to its abnormal position upon the tilting of the housing 14 to an angle corresponding to the angle of inclination of the surface 21 to the horizontal or, in other words, each of the balls will move from its normal or central position when the longitudinal axis of the housing 14 is disposed at an angle to the vertical corresponding to the complement of the angle of inclination of the surface 21 to the longitudinal axis of the housing 14. For example, the uppermost unit 19a may have its conical surface disposed at an angle to the longitudinal axis of the housing 14 of, say, 89½°, while the surface of unit 19b may be disposed at 89°, that for units 19c, 19d and 19e may be disposed at lesser angles in increments of ½° each so as to accurately measure deviations from ½° up to at least 3°. Then if the well bore deviates by 1° from the true vertical, units 19a and 19b will have been tilted sufficiently to move their associated balls 22 from their central positions and into contact with the respective contact rings 24 while units 19c, 19d and 19e will not have been tilted sufficiently to move the balls from their normal positions or into contact with their contact rings. Thus the number of balls which have been moved from normal to abnormal position constitutes a detector denoting that the well bore deviates from the vertical and also constitutes a measuring device which measures the angle of such deviation. While the shifting of the balls in itself constitutes the detecting and measuring portions of the instrument and may be employed as a measure of the angle of deviation of the well bore, we prefer to associate the shifting movement of the balls with suitable translating mechanism which will translate the movement of the balls from one of their positions to the other as intelligence receivable and translatable at the ground surface. For this purpose we prefer to provide sound transmitting apparatus which will be actuated in differing predetermined manners dependent upon the number of balls which have been shifted from their normal to their abnormal positions.

As illustrated particularly in Figs. 4, 6 and 7, this sound transmitting apparatus may comprise a buzzer or vibrator 28. We prefer to employ an electrically actuated vibrator because the same can be constructed of such rugged character as to withstand shocks, vibrations and other conditions which might interfere with or destroy the usefulness of other types of vibrating mechanisms. The sound transmitting apparatus illus-

trated herein includes a suitable core 29 about which is wound an electro-magnetic coil 30 enclosed within a suitable casing 31 in which is mounted, as by a pivot 32, a movable armature 33. The armature 33 is adapted to bear upon a spring contact member 34 and normally press the contact point 35 thereof into engagement with a stationary contact 36 but which, when attracted by the core 29, will allow the contact 35 to move away from the contact 36 and thereby open the circuit to the coil 30 in the manner usually employed in electrical vibrators.

The core 29 has preferably associated therewith a non-magnetic head 37, against which the armature 33 may strike when attracted by the coil 30 so that each time the coil is energized the armature 33 will strike a considerable blow against the head 37, which blow will be transmitted through the metallic parts of the vibrator as a sound vibration. By selecting the distance through which the armature must move and by selecting the mass of the armature as compared with the strength of the coil 30, the vibrator 28 may be caused to actuate at any predetermined frequency to produce a sound vibration of predetermined frequency. The assembly of the vibrator 28 within the housing 14 is preferably accomplished by forming the casing 31 so that it makes a snug fit within the housing 14 and allowing the casing 31 to abut at its lower end upon a disc 38 of insulating material, which disc may constitute the mounting means for the spring 34 and the contact 36.

Disposed immediately below the disc 38 is an insulating ring 39 having a recess 40 therein cooperating with a recess 40a in an insulating sleeve 41 so as to hold between the recesses 40 and 40a a continuous contact ring 42. Set within and distributed about the insulating sleeve 41 is a plurality of short segmental contact members 43a, 43b, 43c, 43d and 43e, these contact segments being distributed evenly about the inner circumference of the sleeve 41 and disposed a short distance away from the contact ring 42 so that a bridge member 44 when rotated in a horizontal plane will successively connect each of the contact members 43a, etc. with the contact ring 42.

As will be understood, there is a contact segment 43a, etc. for each of the units 19a, 19b, etc. employed in the instrument so that the contact ring 24 of the unit 19a may be connected by a suitable conductor 45a to the contact segment 43a while the contact rings 24 of each of the units 19b, 19c, 19d, etc. are respectively connected by means of conductors 45b, 45c, etc., with respective contact segments 43b, 43c, etc.

In the form of the device shown in Figs. 4 and 7, a motor or other rotating device 46 may be employed to successively bridge between the contact segments 43a, etc. and the contact ring 42, this motor being set into a recess 47 in the insulating sleeve 41, the upper end of the motor 46 abutting a shoulder 48 to prevent upward movement thereof relative to the sleeve 41 while a metallic disc 49 having a diameter snugly fitting the interior circumference of the housing 14 may abut the lower end of the motor and hold the motor against downward displacement.

Electric power may be supplied to the motor and to the vibrator 28 from a suitable dry cell battery 50 which may be located within the lower end of the housing 14, held in place therein by the lower cap 16 and having one of its terminals grounded upon the cap 16 while the other of its terminals 51 engages a contact button 52 which

is in turn connected by means of a conductor 53 to one terminal 54 of the motor and to one terminal of the vibrator coil 30.

The interconnection between the battery 50, the vibrator 28 and the angle detecting units 19a, etc., is illustrated diagrammatically in Fig. 7 wherein each of the supporting plates or discs 20 is illustrated as being grounded so that movement of the ball 22 associated with unit 19a will partially complete an electric circuit to the vibrator 28, which circuit will be completed when the contact brush or bridge 44 bridges the contact segment 43a associated with that unit 19a. Assuming that the instrument, disposed with its longitudinal axis parallel to the longitudinal axis of the well bore, is tilted at such angle that the contact ball 22 associated with unit 19a is engaging its contact ring 24, a circuit will be completed which extends from the battery 50, through a switch 55, conductors 53 and 56 to the coil 30 of the vibrator 28, whence the circuit extends by means of conductor 57 to the contact spring 34, contacts 35 and 36, conductor 58, to contact ring 42. When the brush or bridge 44 bridges contact segment 43a and ring 42, the circuit will be completed through conductor 45a, the contact ring 24 being associated with unit 19a, ball 22, and metallic disc 20 to ground, the opposite terminal of the battery 50 being grounded as indicated at 16. The vibrator will then be caused to operate to produce sound vibrations of predetermined frequency.

In order to avoid unnecessary depletion of the battery 50, a switch 55 of the character shown and described in Anschutz-Kaempfe United States Patent No. 1,313,367, may be employed, arranged to maintain its contacts open whenever the instrument is subjected to vibrations such as those encountered in ordinary drilling operations, but which will close its contacts when those vibrations have ceased.

The motor 46, being supplied with current from the battery 50, through switch 55, conductor 53, the field winding 46a and armature 46b of the motor 46 to an auxiliary grounded contact segment 59 comprising an additional segment in the group 43a, 43b, etc. will operate continuously and successively connect the segments 43a, 43b, etc. to ring 42. We prefer to employ the additional contact segment 59 as a monitor to produce one beat in each revolution of the brush 44 to indicate to the listener or operator that the motor 46 is functioning. In other words, upon each rotation of the brush 44, one beat or series of vibrations will be produced whether or not the instrument has been tilted away from the vertical, notifying the operator that the instrument is in operative condition, and then if the instrument has been tilted from the vertical by reason of deviation of the well bore from the true vertical, for example, sufficient only to move the ball 22 of unit 19a, a second beat or series of vibrations will be produced upon each rotation of the brush 44.

Thus if only one of the balls 22 has been moved to its abnormal position, there will be only two series of vibrations produced upon each revolution of the contact brush 44 while, if others of the balls 22 have been moved to abnormal position, there will be a series of beats or a series of groups of vibrations produced upon each revolution of the brush 44, the number of these beats depending upon the number of balls which have been moved. Thus by listening to the sound produced there will be received an indication of

the angle of inclination of the well bore, the measure of which angle depends upon the number of beats per cycle of rotation of the brush 44.

For example, if three beats followed by a long pause is heard, this will be an indication that units 19a and 19b have been tilted to such angle that the balls 22 associated therewith are in abnormal position and that the angle of inclination is 1° from the vertical since only at this angle will both of the balls 22 associated with units 19a and 19b be in abnormal position while the balls 22 of the remaining units will be in their normal central positions. Again, if four beats followed by a pause is heard, it will be an indication that the angle of inclination of the well bore from the vertical is equal to the angle selected for the surface of unit 19c.

These vibrations may be transmitted to the ground surface as electrical vibrations or sound vibrations as desired though, in order to avoid the necessity of providing conductors extending down through the well bore, we prefer that the sound vibrations be transmitted upwardly through the metallic parts of the drill string, casing or other metal which extends into the well bore.

A convenient way in which to receive these sound vibrations and to segregate the predetermined frequency vibration produced by the vibrator 28 from any other extraneous vibrations is illustrated in Fig. 6 wherein a microphone 60 is illustrated as being placed against some metallic part of the drill string or its supporting mechanism, preferably against either the gooseneck 61 for the mud hose or some other part of the metallic portions of the well drilling structure which will not be rotated during the normal drilling operations. The microphone 60 will receive the sound vibrations emanating from the vibrator 28 and will pass these vibrations as electrical vibrations to a filter 62 by means of conductors 63. The filter 62 may be of any character well known in the radio art which will filter out all vibrations other than those of a predetermined frequency band, allowing only the electrical vibrations of the desired frequencies to pass to a suitable amplifier 64 at which the vibrations will be amplified at least to an extent capable of permitting them to be detected by earphones or other receiving apparatus 65. Thus by listening at the earphones or loud speaker 65, the operator will be able to determine instantly whether or not the well hole deviates from the vertical and to what extent. If desired, an electrical recording apparatus 66 of any of the well known characters may be employed to produce a permanent record 67 of the impulses or beats received from our instrument below the ground surface.

It will be observed from an inspection of Figs. 4, 5, 6 and 7 that all of the parts of the instrument contained within the housing 4 may be made of relatively rugged character and that there are no delicate bearings, pendulums or other devices which are incapable of withstanding great shocks, great vibration and considerable abuse. The balls 22 may be made of hardened steel and the disc supports 28 may be made of hardened steel. The diameter of the casing 14 may be relatively small, as small as $\frac{1}{2}$ inch, so that the total distance through which any of the balls 22 move between their normal and abnormal positions may be so small as to prevent the building up of any appreciable amount of kinetic energy and thus the strength of all of the parts relative to the mass of all of the parts may be maintained

at a high value. Again it will be noted that there is nothing in the apparatus thus far described which cannot withstand falls, shocks or other abuse so long as such abuse is insufficient to completely crush the shell of the housing 14.

By reason of the rugged character of the instrument thus far described, it will be apparent that one important advantage is that it may be permanently associated with the drilling tools and allowed to remain in the hole during the normal drilling operations, requiring only that the drilling operations be paused long enough for the balls 22 in the instrument to come to rest in order to produce the desired indications of whether or not the hole has deviated from the vertical and to what extent.

For example, as illustrated in Figs. 1, 2 and 3 herein, the housing 14 may be detachably fixed within a recess 68 in the drilling sub 3 normally employed immediately above the drill bit 2.

By reason of the fact that our instrument may be made of relatively small diameter, the entire housing 14 may be contained within a relatively small diameter and shallow recess in the side wall of the sub 3 out of the way of mud fluid which is passing down through the usual circulation opening 69 in the sub 3 and equally out of the way of the mud fluid passing up about the exterior of the drill bit and sub. For example, as shown in Figs. 2 and 3, a shallow recess 68 may be cut into the side wall of the sub 3 just sufficiently deep to permit the complete enclosure of the housing 14 within the circle described by the exterior circumference of the sub 3 and the instrument may be maintained within this recess by means of a suitable cap 16 removably attached to the sub 3 as by bolts 71. As will be understood by those skilled in the art, the sub 3 is relatively long so that ample space is provided thereon for a relatively long housing 14 but the cross sectional area of the sub 3 is limited by the diameter of the hole and also by the diameter of the wash opening 69. Thus our instrument, being capable of construction of relatively small diameter and of sufficient length to accommodate all of the apparatus contained within the housing 14, is readily adapted to be detachably fixed to the bit, sub or other drilling tool. It will be noted that the disposition of the recess 68 and the mounting of the housing 14 therein is such that the longitudinal axis of the housing 14 is always maintained parallel to the longitudinal axis of the bit, sub or drill string so that if the axis of the bore deviates from the vertical, the longitudinal axis of the bit, sub or lower portion of the drill string will also deviate from the vertical in the same manner and to the same degree and thus will dispose the longitudinal axis of the housing 14 at the same angle to the vertical as the axis of the well bore deviates from the vertical.

It will also be noted that by reason of the rugged character of all of the parts of our instrument, this instrument may be either dropped down from the ground surface through the wash opening in the drill string and allowed to fall therethrough freely by gravity without danger of breakage or disability and avoiding the necessity of providing cushioning devices or mechanism heretofore required by all other instruments of this character. In other words, the instrument may be dropped freely through the wash opening of the drill pipe and as it falls therethrough the displacement of the drilling fluid will tend to retard the gravity fall of the

instrument while when the instrument arrives at the lower end of the hole it will come to rest upon the drill bit and, even though it should be brought to rest with considerable rapidity, the shock thereof will be well below any possibility of breakage of the instrument.

On the other hand, it may be desired to lower the instrument from the ground surface upon a cable or wire as is illustrated particularly in Fig. 16, the housing 14 having upon its upper end a suitable coupling 72 to which the wire, cord or cable 13 may connect and the housing 14 preferably having an external diameter somewhat smaller than the diameter of the wash opening 69 in the drill string sub and bit so that by providing spring fingers 74 distributed about the housing 14, the housing 14 will be maintained with its longitudinal axis aligned with the longitudinal axis of that part of the drill string through which it is passing or at which it has come to rest.

While we prefer to employ units 19a, 19b, etc., having conical depressed surfaces 21, it will be apparent to those skilled in the art that other types or configurations of surfaces may be employed; for example, a concave surface. The curvature of this surface in one of the units may be described by a given diameter so that it will be necessary to tilt the instrument to at least an angle of 1° from the vertical in order for the ball to move from a central or normal position thereon while the curvature of the surfaces of the other units may be of progressively lesser diameter, requiring the tilting of the instrument to a greater angle before the balls will move to their abnormal or contacting positions.

However, by employing the conical depressed surface, it will be apparent that the balls will remain in their central or normal positions until the instrument has been tipped to an angle complementary to the angle of inclination of the surface relative to the vertical before the ball will start to move and then when the instrument has been tipped or tilted to this position the balls will move from their central or normal position to their abnormal or contacting position. In other words, by employing a surface of this character the balls will move only when the instrument is tilted to an angle equal to the complement of the angle of inclination of the surface 21 to the longitudinal axis of the instrument.

Other types of devices which will accomplish this same result of permitting movement of the ball between its two positions only upon tilting of the instrument to a predetermined angle are illustrated in Figs. 8 and 9 wherein Fig. 8 shows the supporting disc 20a as having a flat plane upper surface 21a disposed in a plane transverse to the longitudinal axis of the instrument and is provided near its center with a depression 75 into which the ball 22 may seat when in its normal or central position. By varying the depth of the depression 75, it will require tilting of the instrument to different angles in order to allow the ball 22 to move by gravity out of the depression and into contact with the contact ring 24 associated with the detecting unit.

In Fig. 9 we have illustrated the surface of the supporting disc 20b as combining the depressed conical surface 21 with the depression 75, thus permitting all of the units to be constructed with their surfaces 21 with the same conical depression but permitting the variation of the depth of the depression 75 to control or determine the angle to which the instrument

must be tilted before the ball 22 will move from its central or normal position.

In Figs. 10 and 11 we have illustrated a slightly modified form of surface which may be used, in which the supporting disc 20c is provided with a pair of transversely extending slots of sufficient width to allow the ball to roll along any of the slots from the lowermost point 76 (disposed near the central axis of the disc 20c). In this case the ball 22 is not free to roll in all directions but may roll in any one of four directions from the center 76 toward the contact ring 24. It will be apparent that if desired a cylindrical roller or other shape of rolling member may be substituted for the ball provided only that the rolling member must be capable of freely rolling on the surface 21 by gravity.

In some instances it may be desirable, once the ball 22 has been moved from its central or normal position, that it should be maintained in its abnormal position until the instrument has been withdrawn from the well bore, in which case the supporting disc 20d may be employed as shown in Fig. 12 wherein the surface 21d has a depression 77 near its center and also is depressed near the outer circumference as indicated at 78. The ball, once moved from the central position, will remain in its abnormal position, indicated in dotted lines in Fig. 12.

Also it may be desirable in some instances to substitute a closed circuit electrical system for the open circuit electrical system shown in Fig. 7. Such arrangement is shown in Figs. 12 and 13 herein wherein each of the supporting discs 20d is provided at its center with a central bore 79 into which may be pressed a bushing 80 of insulating material. A contact pin 81 may project upwardly through the bushing 80 and be normally urged upwardly by means of a spring 82, insufficient in strength, however, to overcome the weight of the ball 22 when the ball is in its normal or central position. Thus whenever the ball 22 is in normal position the ball will contact the surface 21d and the contact pin 81, closing the electrical circuit at this point. Referring now to Fig. 13, it will be observed that the electrical circuit controlled by the balls 22 constitutes a closed circuit extending from the battery 80 through switch 55 and conductor 83, from which branch circuits extend to each of the units 19a, 19b, 19c, etc. One of these circuits extends by way of conductor 84, the coil of a relay 85, conductor 86, to the contact pin 81 associated with the disc 20d on unit 19a; whence the circuit extends through the ball 22 and the disc 20d to ground at 87. The relay 85, being normally energized whenever the ball 22 is in central or normal position, will hold its contacts open, preventing the establishment of a circuit to the vibrator 28 until the ball has been moved from its normal to its abnormal position.

The circuit thus far described may be substituted for the electrical connections shown in Fig. 7 between the units 19a, 19b, 19c, etc. and the contact segments 43a, 43b, 43c, etc. merely by connecting the contacts of the relays 85 associated with each of the units 19a, 19b, 19c, etc., with the respective contact segments 43a, 43b, 43c, etc.

In Fig. 13, however, we have illustrated a substitute electrical system, permitting the motor 46 to be dispensed with and illustrating the manner in which each of the units 19a, 19b, 19c, etc. may be successively connected to the vibrator 28 without the necessity of rotary commutators or

other segment and brush contacts, such as 42, 43a, and 44 shown in Fig. 7.

In Fig. 13 we have illustrated such substitute electrical system as being applied to three detector units 19a, 19b, 19c, etc. though it will be understood that as many more units may be employed as is desired in a completed instrument. Associated with each of the units 19a, 19b, 19c, etc. is a relay which may be constructed of such rugged character as to insure its successful operation under the most trying conditions of abuse. One of these relays A is associated with unit 19a, a second relay B is associated with unit 19b, and a third relay C is associated with unit 19c so that by connecting the relays A, B, C to operate in sequential relation with respect to each other in a predetermined time cycle, these relays will during each cycle connect its associated unit with the vibrator 28. This may be readily accomplished as is illustrated in Fig. 13 by connecting the coil of the relay A to be energized a predetermined time period after the relay C has been energized and connecting the coil of the relay B to be energized at a predetermined time after relay A has been energized and so on throughout the entire cycle, each relay when actuated serving to prepare the circuit for the next relay and also serving to de-energize the preceding relay in the cycle.

For example, the coil of the relay A may be connected in an electrical circuit which extends from the battery 50 through conductors 83, 88 and 89 to the lowermost contacts of relay B (arranged to be closed whenever relay B is deenergized and arranged to be opened whenever relay B is energized). Thence the circuit extends by way of conductor 90 to the coil of relay A, whence the circuit extends by way of conductor 91 to the contacts b on relay C, conductors 92 and 93 to normally close contacts b on a timing relay T and thence by way of conductor 94 to ground at 95.

Thus whenever relay C is energized, as will be described hereinafter, its contacts b will prepare a circuit for the coil of relay A, which circuit will be completed as soon as timing relay T closes its normally closed contacts b.

In order to prevent the energization of relay A until a predetermined time period after relay C has been actuated, the timing relay T is arranged with a dash pot or other retarding device to momentarily close its normally closed contacts after deenergization of the coil of said relay in any manner well known in the art. This time delay may be selected as of any desired value though we prefer that the same be only a matter of a fraction of a second, sufficient only to permit the distinction between successive beats produced by the vibrator 28.

The relay T is therefore arranged to be actuated repeatedly at regular intervals, which may be readily accomplished by providing a control relay for the timing relay T indicated herein as relay TR. Relay TR has its coil connected in a circuit extending from the battery 50, through conductor 83, conductor 96, normally closed contacts a of relay T, conductor 97, coil of relay TR and conductors 98 and 99 to ground at 95. Relay TR will therefore be energized whenever relay T has been deenergized and the time relay imposed upon relay T has expired. Relay TR when energized closes its contacts to complete an energizing circuit for relay T, which circuit extends from the battery 50, through conductor 83, conductor 100, the coil of relay T, conductor 75

101, the contacts of relay TR and conductors 102 and 99, to ground at 95. Relay TR closing its contacts energizes relay T; relay T when energized opens the circuit for relay TR, thus de-energizing relay T. By properly selecting the time delays in the operation of the relays T and TR, relay T may be arranged to close contacts b momentarily a given number of times in a predetermined time cycle.

Thus relay C, having prepared the circuit for relay A, will cause energization of relay A upon the next closing of contact b on the time relay T. Relay A when energized closes its contacts a to provide a self-holding circuit for relay A to maintain this relay energized until the holding circuit is opened. This circuit extends from the battery 50, through conductors 83, 88, 89, the normally closed contacts on relay B, conductor 90, to the coil of relay A, as hereinbefore described, whence the circuit extends by way of conductor 103 to the contact a on relay A, conductors 104 and 105, to ground at 106.

Relay A when energized also closes its contacts c which couples unit 19a to the vibrator 28, this circuit extending from the battery 50, through conductors 83 and 107, vibrator 28, conductor 108, contacts c on relay T, conductor 109, contact c on relay A, conductor 110 to the contacts of relay 85, which contacts will be open if the ball 22 of unit 19a is in its normal position but will be closed if this ball is in abnormal position. If the ball is in abnormal position, the circuit is completed through the contacts of relay 85 to ground at 111 and as soon as relay T again picks up the vibrator 28 will be actuated to give one beat or series of vibrations.

Relay A when actuated prepares a circuit for relay B similar to the circuit which was prepared for relay A by relay C, this circuit being completed upon the next operation of timing relay T. As soon as timing relay T again operates to close its contacts b, relay B will pick up and in so doing will open its normally closed contacts d, interrupting the previously completed self-holding circuit for the relay A, allowing relay A to drop out and remain deenergized until relay C has again been actuated.

Relay B upon closing also completes a self-holding circuit similar to that described for relay A and also closes at its contacts c a circuit which connects or couples the unit 19b with the vibrator 28, causing the vibrator to produce a series of vibrations or a beat if the ball 22 associated with unit 19b is in its abnormal position.

Likewise relay B when energized partially completes a circuit for relay C, which circuit can only be completed, however, upon the subsequent actuation of relay T. Relay C, like relay B, has its normally closed contacts c in the self-holding circuit for relay B so that as soon as relay C is energized, relay B is cut out. Relay C has its contacts c connected with the unit 19c so as to couple this unit with the vibrator 28 and, if the ball 22 associated therewith is in abnormal position, a third series of vibrations or beats will be produced by the vibrator 28.

It follows therefore that once relays A, B and C have been set into actuation by the energizing of any one of these relays, they will continue to operate in sequence A, B, C, A, B, C, until the circuit is opened at switch 55, producing the same result of sequentially connecting the several inclination detecting units 19a, 19b, etc. with the vibrator 28 so that the signal produced will be a series of vibrations or beats, the number of

which will depend upon the number of detector units 19a, 19b, etc., which have had their rollers, balls or other movable devices moved to abnormal position by reason of the inclination of the well bore.

In order to start the sequence of operations of relays A, B and C, we prefer to provide on the switch 55 additional contacts indicated diagrammatically as switch 112, which may be arranged upon the structure of switch 55 so as to be momentarily closed when switch 55 is closed but to immediately thereafter open.

The switch 112 is illustrated as being connected in a circuit shunting contact *a* of relay A so that an initial energizing impulse is given to relay A and then, as soon as relay A has once been operated, the sequential operation of relays A, B and C will follow.

The various detector units 19a, 19b, etc. may be connected to the segmental contacts 43a, 43b, etc. in the form of the device shown in Fig. 4 or with the sequential units A, B, C, in the form of the device shown in Fig. 13 by suitable conductors which may extend through the slots 115 in the supporting discs 20 and in the insulation rings 25 and 26 (see Fig. 4), these slots being aligned with each other in such manner as to form a conduit through which the conductors may pass. Similarly, the battery 50 may be interconnected with the motor 46 and the vibrator 28 by means of a conductor 53 which extends upwardly through conduit slots 116 in the discs 20 and insulation rings 25 and 26. Likewise in the form of the device shown in Fig. 13, conductor 83 which leads upwardly to supply current to the various relays, may pass through the slot 116 in the same manner as described for the motor and vibrator circuit conductor.

However, in order to adapt our instrument to ready adjustment for any desired number of detector units, we may employ the arrangement shown in Figs. 14 and 15 wherein each of the detector units 19x is illustrated as comprising a relatively deep ring of insulation material 117 formed with an annular interior recess 118 into which the supporting disc 20 may seat against a radial flange 119, with a tongue 20y extending to the exterior surface of ring 117 to make grounded contact with the housing 14. A second ring of insulation material 120 is secured directly upon the ring 117 having a recess 122 cooperating with a recess 123 in ring 117 to act as a seat for the contact ring 24x. The rings 117 and 120 may be held together by means of rivets 124 which are preferably constructed as shown in Fig. 15, of an elongated tubular portion extending through the rings 120 and 117 and having their lower ends 125 peened out to form a flared entrance opening thereof and to rivet these tubular members in place. The upper ends of rivets 124 may be provided with enlarged shoulders 126, from which pins 127 extend upwardly, of such diameter as to be readily received within the openings at the lower ends of tubular rivets associated with another one of the detector units 19x.

As is illustrated in Figs. 14 and 15, eight of these rivets may be distributed in evenly spaced relation about the circle described by the units 19x, all of the rivets 124 except one extending entirely through the unit to receive the pins from another unit disposed below the first unit. One of these rivets 124x is short, extending only through the ring 120, and is connected as by soldering or otherwise to the contact ring 24x, 75

as indicated at 128. Immediately below the short rivet 120 the ring 117 is provided with a short bore or opening 129 capable of receiving the pin 127 of a rivet on the next lowermost unit in the assembly.

By employing the construction shown in Figs. 14 and 15, it will be apparent that the rivets constitute plug and jack connections by which six units may be assembled one upon the other, one of the rivets 124 of the lowermost unit acting as a conductor for the power supply line 53 while its short rivet 124x plugs into a long rivet in the unit assembled immediately above it. A third unit may be plugged in upon the second unit, a fourth unit upon the third, and so on, care being taken only to rotate each of the uppermost units $\frac{1}{8}$ of a revolution before plugging in so as to plug the short rivet of each unit into a long rivet into the next uppermost unit, without interfering with or interrupting the circuits extending upwardly from all of the lower units.

It will be observed therefore that we have provided a measuring device for detecting and measuring the angle of inclination of a well bore which may be constructed of such rugged material and which has all of its parts made of such rugged character that the instrument may be handled with a small amount of care and may be subjected to considerable abuse without danger of injury to any of the parts. It will also be noted that our unit is of such small diameter that it may be readily fixed to any of the well known drilling tools or other tools which are sent down through the well bore so that by the mere stopping of the rotary drilling for a few seconds, giving the switch 55 time to close its contacts, an indication of the condition of the well bore may be made at any time. By reason of this construction, allowing a small diameter for the instrument, it may be either dropped from the surface when an indication is desired or it may be lowered upon a cable or wire when an indication is desired, the instrument passing down through the usual mud fluid bore in the drilling apparatus and, by reason of its rugged character, the instrument may be dropped rapidly and allowed to strike the bottom of the well bore or the tools at the bottom of the well bore without injury even though no cushioning apparatus is employed.

It will also be noted that by employing our instrument the smallest deviation of the well bore from the true vertical will be immediately transmitted to the surface of the well where it may be detected and translated, giving the operator sufficient information to allow him to straighten the well bore and prevent further deviation thereof.

While we have shown and described the preferred embodiment of our invention, we do not desire to be limited to any of the details illustrated or described herein except as defined in the appended claims.

We claim:

1. In a device for measuring the inclination of a well bore, a body member insertable in said well bore and adapted to dispose the longitudinal axis of said body member parallel with the axis of said bore; a plurality of movable means in said body member each movable from a normal position to an abnormal position upon inclination of said axis of said body member from the vertical at an angle different from that of the others of said means; an indicating device; a plurality of electric circuits, one for each of said

movable means, each of said circuits including means for energizing that circuit actuated by movement of the associated movable means to an abnormal position; and means for consecutively connecting said indicating device to said circuits for actuation by each of said energized circuits whereby the number of actuations of said indicating device indicates the angle of inclination of the said housing from the vertical.

2. In a device for measuring the inclination of a well bore, a body member insertable in said well bore and adapted to dispose its longitudinal axis of said body member parallel with the axis of said bore; a plurality of movable means in said body member each movable from a normal position to an abnormal position upon inclination of said axis of said body member from the vertical at an angle different from that of the others of said means; an indicating device; a plurality of electric circuits, one for each of said movable means, each of said circuits including means for energizing that circuit actuated by movement of the associated movable means to an abnormal position; and means for repeatedly connecting said indicating device to said electric circuits consecutively in a predetermined time cycle, whereby the number of actuations of said indicating device in said cycle indicates the angle of the inclination of said housing from the vertical.

3. In a device for measuring the inclination of a well bore, a body member insertable in said well bore and adapted to dispose its longitudinal axis parallel with the axis of said bore, means movable from a normal position when said axis is vertical to an abnormal position when said axis is inclined to the vertical, mechanism actuated by movement of said means from said normal position for producing a signal of predetermined frequency, and translating means for receiving and translating said signal and a means associated therewith for preventing response of said translating means to any frequency other than said predetermined frequency.

4. In a device for measuring the inclination of a well bore, a body member insertable in said well bore and adapted to dispose its longitudinal axis parallel with the axis of said bore, means movable from a normal position when said axis is vertical to an abnormal position when said axis is inclined to the vertical, mechanism actuated by movement of said means from said normal position for producing a sound vibration of predetermined frequency, sound responsive means for receiving and translating said vibrations and having means associated therewith for preventing response of said sound responsive means to any frequency other than said predetermined frequency.

5. In a device for measuring the inclination of a well bore, a body member insertable in said well bore and adapted to dispose its longitudinal axis parallel with the axis of said bore, means movable from a normal position when said axis is vertical to an abnormal position when said axis is inclined to the vertical, mechanism actuated by movement of said means from said normal position for producing a sound vibration of predetermined frequency, sound responsive means for receiving and translating said vibrations and having filter means for filtering out all frequencies other than said predetermined frequency.

6. In a device for measuring the inclination of a well bore, a body member insertable in said

well bore and adapted to dispose its longitudinal axis parallel with the axis of said bore, a plurality of movable means in said body member, each movable from a normal position to an abnormal position upon the inclination to the vertical of said axis of said body member at an angle different from the angles at which the others of said means are movable, indicating means associated with said movable means for indicating the disposition of any of said movable means from normal position, and means for consecutively coupling said movable means to said indicating means whereby the number of said movable means disposed in abnormal position may be indicated.

7. In a device for measuring the inclination of a well bore, a body member insertable in said well bore and adapted to dispose its longitudinal axis parallel with the axis of said bore, a plurality of movable means in said body member, each movable from a normal position to an abnormal position upon the inclination to the vertical of said axis of said body member at an angle different from the angles at which the others of said means are movable, signal means for producing a signal associated with said movable means to be actuated by any of said movable means disposed away from its normal position, and means for consecutively coupling said movable means to said signal means to produce a series of signals the number of which indicates the angle of inclination of said bore to the vertical.

8. In a device for measuring the inclination of a well bore, a body member insertable in said well bore and adapted to dispose its longitudinal axis parallel with the axis of said bore, a plurality of movable means in said body member, each movable from a normal position to an abnormal position upon the inclination to the vertical of said axis of said body member at an angle different from the angles at which the others of said means are movable, indicating means associated with said movable means and actuated in response to the disposition of any of said movable means away from its normal position, an electrical circuit for actuating said indicating means including a branch circuit for each of said movable means, and means for consecutively coupling said branch circuits to said indicating means whereby said indicating means will produce a series of indications the number of which corresponds to the number of said movable means disposed in abnormal position.

9. In a device for measuring the inclination of a well bore, the combination of a self-contained instrument insertable in the well bore including, a plurality of movable means each movable from a normal position to an abnormal position upon inclination to the vertical of the axis of said instrument at an angle different from the angles at which the others of said means are movable, signal producing means associated with each of said movable means and actuated thereby when said movable means is in abnormal position; and means at the ground surface for receiving the signals produced by said signal producing means for determining which of said movable means has been moved to abnormal position to thereby indicate the angle of inclination of said instrument from the vertical.

10. In a device for measuring the inclination of a well bore, the combination of a self-contained instrument insertable in the well bore including, a plurality of movable means each movable from a normal position to an abnormal position upon

inclination to the vertical of the axis of said instrument at an angle different from the angles at which the others of said means are movable, signal producing means associated with each of said movable means and actuated thereby when said movable means is in abnormal position, and means independent of said movable means for actuating said signal producing means; and means at the ground surface for receiving the signals produced by said movable means and by said independent means for determining operativeness of the instrument and for determining which of said movable means has been moved to abnormal position.

11. In a device for measuring the inclination of a well bore, a body member insertable in said well bore and adapted to dispose the longitudinal axis of said body member parallel with the axis of said bore; a plurality of movable means in said body member each movable from a normal position to an abnormal position upon inclination of said axis of said body member from the vertical at an angle different from that of the others of said means; an indicating device, a plurality of electric circuits, one for each of said movable means, each of said circuits including means for energizing that circuit actuated by movement of the associated movable means to an abnormal position; an additional circuit including means normally energizing the same; and means for consecutively connecting said indicating device to said circuits for actuation by each of said energized circuits whereby the number of actuations of said indicating device indicates operativeness of the instrument and the angle of inclination of the said housing from the vertical.

12. In a self-contained unit for determining the inclination of a bore hole from the vertical, a casing containing therein the following instrumentalities; a source of electrical energy, a plurality of movable members movable from a normal position to an abnormal position upon inclination of said casing from the vertical, each member being movable upon inclination of the

- casing from vertical at an angle different from the angles at which the other members are movable and each member having means for completing a partial circuit including said source, an electrically operated sound generating device and means for repeatedly sequentially completing through the generating device the partial circuits capable of being prepared by the movable members, whereby the number of partial circuits prepared by said members for a given inclination of the casing and completed by the sequence means during each repetition is manifested by the number of operations of the generating device for each repetition.
13. In an oil well instrument, means actuatable to measure conditions in a well bore, signalling means operable in response to actuation of said measuring means to transmit to the ground surface signals the number of which is representative of the measurements made thereby, actuating means operable to actuate said measuring means, and means responsive to operation of said actuating means for operating said signalling means independently of the actuation of said measuring means to thereby produce another signal indicating the operative condition of said signalling means.
14. In an oil well instrument, means actuatable to measure conditions in a well bore, signalling means operable in response to actuation of said measuring means to transmit to the ground surface sound signals the number of which is representative of the condition measured by said measuring means, actuating means operable to actuate said measuring means, and means responsive to operation of said actuating means for operating said signalling means independently of the actuation of said measuring means to thereby produce another sound signal indicating the operative condition of said signalling means.
